Primary Examiner — George J Ulsh*Assistant Examiner* — Andrea Marie McKay(74) *Attorney, Agent, or Firm* — Etherton Law Group, LLC(57) **CLAIM**

The ornamental design for a vent for a concrete tile roof, as shown and described.

DESCRIPTION

FIG. 1 is a top perspective view of my vent for a concrete tile roof, showing the new design.

FIG. 2 is a bottom perspective view thereof;

FIG. 3 is a front elevation view thereof;

FIG. 4 is a rear elevation view thereof;

FIG. 5 is a right side elevation view thereof;

FIG. 6 is a left side elevation view thereof;

FIG. 7 is a top plan view thereof;

FIG. 8 is a bottom plan view thereof; and,

FIG. 9 is a sectional view thereof along line 9-9 of FIG. 8. The broken lines in FIGS. 1-8 show features forming no part of the claimed design.

1 Claim, 7 Drawing Sheets(56)
